METHOD OF TUFTING AND ARTICLES
THEREFOR

Annette Fridolph, New York, N. Y., assignor to
A. B. A. Specialties Company, Inc., New York,
N. Y., a corporation of New York

Application June 8, 1931, Serial No. 542,799

14 Claims. (Cl. 5—356)

This invention relates to improvements in methods of tufting mattresses, upholstery and the like, and articles to be used for such operations. The principal objects of the invention include a new and improved method whereby the tufting operation may be accomplished quickly, cheaply and expeditiously, and in which the articles used are securely fastened in proper position to give the proper tufting effect and appearance.

10 The tufting element disclosed in this application forms the subject of a divisional application filed October 23, 1936, Serial No. 107,122.

To the accomplishment of the foregoing and such other objects as may hereinafter appear, this invention consists in the method hereinafter described and then sought to be defined in the appended claims, reference being had to the accompanying drawings forming a part hereof and which show, merely for the purpose of illustrative disclosure, several embodiments of my invention, it being expressly understood, however, that various changes may be made in practice within the scope of the claims without digressing from my inventive idea.

25 In the drawings—

Figure 1 represents a perspective view of one form of tufting element.

Figure 2 represents a perspective view of another form of tufting element.

30 Figure 3 is a vertical transverse cross section taken along line 3—3 of Figure 2.

Figure 4 is a similar cross section showing a slightly modified form.

Figures 5 and 6 are detailed views showing a 35 modified form of tufting button attached to the tufting element.

Figures 7 and 8 are detailed views showing another modified form of tufting button attached to the tufting element.

40 Figure 9 is a vertical cross section taken substantially on line 9—9 of Figure 1.

Figure 10 is a perspective view of another form of tufting button.

45 Figure 11 illustrates in perspective the initial steps in the method of forming another form of tufting element.

Figure 12 is a vertical cross section through the tufting element and article formed from the parts 50 shown in Figure 11.

Figure 13 is a similar cross section of a modified construction.

Figure 14 is a perspective view of another modification of tufting element.

Figure 15 is a perspective view of the tufting

needle or device used in practicing the method of this invention.

Figure 16 is a diagrammatic view of the completed article.

Figure 17 is a vertical cross section of a globular 5 form of tufting button showing the tufting element in the process of being inserted therein.

Figure 18 is a side elevation of the completed tufting article and element shown in Figure 17.

Figure 19 is a side elevation of the tufting 10 article with another form of button secured thereto.

Figure 20 is an elevation at right angles to the view shown in Figure 19.

Figures 21 and 22 are views similar to Figures 15 19 and 20 of another modification.

Figures 23 and 24 are side elevations of other forms of tufting elements with other forms of tufting buttons or articles secured thereto.

Figures 25, 26 and 27 are diagrammatic views 20 illustrating the practice of my method and the use of tufting articles and buttons substantially shown in Figures 21 and 22.

Figures 28 and 29 are views in elevation of additional modifications of tufting elements and 25 tufting buttons.

It has long been standard practice in tufting mattresses, upholstery and the like, to use a loop or tape or twine and secure buttons, clasps, pieces of leather and other articles to these loops to 30 prevent the cutting or tearing of the fabric and to give a finished and ornamental appearance to the tufting element. The operation of tufting and applying these ornamental articles to the tufting elements has been slow and tedious and 35 laborious, and has always added materially to the expense of tufting mattresses, upholstery and the like.

It is the purpose of this invention to provide 40 new forms of tufting elements including, if desired, ornamental articles or heads and which may be used in accordance with my new method, whereby the tufting operation is simplified and cheapened. The result is a much stronger product having long life and wear and which may be 45 varied for purposes of ornamentation and appearance in many ways.

The general method of tufting which I have invented comprises the use of a tufting element 50 which is designated generally by the reference character 1, and which has secured or provided on each end thereof the tufting article 2, see Figure 16 of the drawings. The structure of this tufting element 1 and the tufting articles 2 and various modifications thereof will be described 55

later. In Figure 15, I show a needle or tufting device 3 for applying the tufting element in proper position and for accomplishing the tufting operation. This needle is elongated and provided with the sharp point 4, the head or handle 5 and the elongated slot or recess 6 in its lower portion. The tufting articles 2 are preferably in the form of a head or shoulder member, and the tufting element 1 is restricted in cross section with respect to the width of the tufting article and may be in the form of a twine, tape or even metallic member.

In the practice of my method, the tufting needle 3 is driven entirely through the article being tufted, and the tufting element 1 placed in the position indicated in dotted lines in Figure 15. The tufting needle is then withdrawn from the article being tufted and the lowermost tufting article or head 2 will engage the underside of the mattress or other article 7 being tufted and when the upper tufting article or head 2 is released it will engage the upper surface of the mattress. Sufficient pressure and tension are used in operation to give the desired tufting appearance as indicated diagrammatically in Figure 16. It is seen by the practice of this method, the application of each tufting element is a simple, single operation and may be accomplished quickly and expeditiously in a minimum amount of time by unskilled labor, and with absolute security.

This method may be utilized with various forms of tufting elements and articles, and attention will first be directed to Figure 1, in which the tufting element is preferably in the form of a tape 8 having the tufting articles or heads 9 at each end. These heads are preferably formed by means of a staff channeled member 10 which may be made of metal or other suitable material, and in which and around which is clamped and folded the end portion of the tape 8, see Figure 9 particularly. In this form, the tufting head is completely covered by the fabric of the tufting element and the channel shaped stiff member 10 is permanently and securely fastened to the tape so that the tufting element and its tufting heads form an integral structure.

The construction shown in Figure 2 is quite similar to that of Figure 1 with the exception that the tufting head 9' is flattened, the cross section of Figure 3 showing the arrangement of the stiff element 10' and the folded and infolded portions of the tufting element 8'.

Figure 4 illustrates an additional variation in which the tufting element 8'' is similar and in which the tufting head 9'' is similar, differing only in the shape of the stiffened member 10'' which gives the tufting head a somewhat different appearance.

In the form shown in Figures 5, 6, 7 and 8, the tufting element is designated generally by the reference character 11, and to the end thereof is secured a suitable button or head 12. In the form shown in Figures 5 and 6 the end of the tufting element 11 is inserted within and secured entirely within the button 12, whereas in the structure shown in Figures 7 and 8 the end of the tufting element 11' extends through the button 12'. These buttons may be round, rectangular, or in fact of various shapes and may be molded or cast upon the tufting elements 11 or 11' and suitably ornamented, if desired.

In the form shown in Figure 10, the tufting element is preferably constructed as substantially shown in Figure 1 having the tape or fabric

body 8 and the stiffened head 9. This head 9 fits in a suitable recess or opening 13 formed in a button element or member 14, the tape 8 passing entirely therethrough in a restricted opening or slot whereby the head 9 engages the shoulders 5 formed by the restricted opening or slot entering into the recess 13. This structure, of course, provides for considerable variety from the standpoint of ornamentation and decoration, and has the advantage of ready detachability.

In the forms shown in Figures 11 and 12, the structure is quite similar to that shown in Figures 1, 2 and 3, the most important difference being that the tufting element 15 is formed of a tube of suitable fabric and into one end of which 15 a piece of metal or other suitable material 16 is inserted and then bent into the form shown in Figure 12 so that the fabric 2 is infolded within and covers the bent metallic member 16. This forms an integral tight connection which is 20 very strong and of long life, the parts being folded and clamped together.

In the form shown in Figure 13, the tufting element 17 is tubular or two-ply and has the interior stiffening element 18 and the exterior 25 stiffening element 19 which are bent or clamped, as shown, to provide a tufting article or head having an exterior metal surface which may be ornamented and decorated as desired. The interior and exterior stiffening elements may be 30 provided or formed by using a tubular shaped metal member through which the fabric element 17 may be passed or threaded before the metal member is bent or clamped thereon. Furthermore, the interior stiffening element 18 may be 35 omitted and the exterior element 19 used alone.

In Figure 14 is shown a further modification in which the fabric tufting element 20 is folded or coiled at its ends, as at 21, which may be dipped into a suitable liquid or other compound, which, when it hardens provides the stiffened tufting 40 article or head 22 at each end. Or the coiled or folded ends 21 may be stitched one or more times to reinforce and stiffen them to form the tufting or fastening article.

In Figures 17 and 18, I show a tufting or fastening element, substantially as shown in Figures 1 and 9, that is, it has the tape or other fabric member 8 and the stiffened tufting or fastening article or head 9. A suitable ornamental button 23 is provided with a slot or opening 50 24 through which the stiffened head 9 is inserted. This opening is less in diameter than the length of the stiffened head 9, and consequently the latter is securely locked therein when positioned in its normal crosswise position shown in dotted 55 lines in Figure 18.

In Figures 19 and 20, the same structure of tufting or fastening element is utilized, as described in connection with Figures 17 and 18. In this connection the ornamental button 25 is provided with a groove or socket 26 in its underside into which the stiffened tufting or fastening head 9 slidably fits. It is to be understood that the material of the lower portion of this button 25 may be bendable so that the depending flange 65 27 may be bent to frictionally engage the stiffened head 9 and securely hold the same in position.

In Figures 21 and 22, a similar tufting or fastening element is used in connection with an ornamental button 28 which is provided with a loop 70 of wire or other suitable material 29 less in width than the length of the stiffened head member 9 so that the latter may be inserted therein and

securely held when in crosswise position as clearly shown in Figure 22.

In Figure 23, the tufting element 30 is provided with an eyelet 31 near its end which is adapted to receive the hook 32 formed in the metal member 33 depending from the ornamental button 34. In Figure 24, the tufting element 35 is formed of a coil or spiral spring having a hook 36 at one or both ends adapted to pass through the eye 37 provided by the loop 38 of wire or other suitable material depending from the ornamental button 39.

In Figure 28, the tufting element 40 is in the form of a suitable flexible material having a knot or enlarged knob formed or provided at one or both ends to prevent the withdrawal of the tufting element 40 from the eye or eyes 42 provided by the loop or loops or hooks 43 of wire or other suitable material depending from the ornamental buttons 44. In Figure 29 the tufting element 45 has a hook member 46 secured to one or both ends which is adapted to pass through the eye 47 formed by the loop 48 of metal or other suitable material depending from button 49.

Figures 25, 26, and 27 illustrate my method in connection with the structure shown in Figures 21 and 22. The top button 28 is first placed upon the shank of the needle 3 and then the needle passed through the mattress 7 until slot or recess 30 is exposed beyond the under surface thereof. There one of the stiff tufting heads 9 of the tufting element 8 is placed within the slot or recess 6 of the needle and the other stiff tufting head 9 is passed through the loop 29 of the second button 28. The tufting needle is then withdrawn through the mattress 7 until the slot or recess is exposed beyond the upper surface thereof and the first mentioned tufting head 9 passes through the loop 29 of the first mentioned button 28, 40 when it is released and the parts assume the position shown in Figure 27. This merely shows the use of ornamental buttons in connection with the practice of my method.

Of course it is obvious that the direction of the operation may be reversed, and that the mattress or other body being tufted may be moved with the needles stationary or both may be moved during the tufting operation.

I have referred to the stiffened head in its various forms as a tufting or fastening element or article, and it is to be understood that may serve generally as a button or other fastening device. Furthermore, the so-called complete tufting element may be used as a fastening or connecting element for various purposes, and that the use of the button heads of Figures 10 and 17 to 29 inclusive, makes provision for a wide range of uses where buttons are necessary or desired for either or both fastening or ornamental purposes.

It is to be expressly understood, that, while I have shown and described a number of uses, modifications and varieties of these articles of manufacture, there are many other constructions and uses which come within my broad invention and 65 can be used in the practice of my method.

What I claim is:

1. The method of tufting mattresses, upholstery and the like, which includes passing one end of a completely preformed unitary tufting element comprising a flexible body with a substantial tufting head connected to each end thereof through the article being tufted by means of a needle or the like while the article is under compression so that said tufting heads will upon 75 release of the compressed parts of the article

each be caused to automatically engage opposite faces of the article being tufted with the body of the tufting element passing through the article being tufted.

2. The method of tufting mattresses, upholstery, and the like, employing preformed unitary tufting elements severally consisting of two heads united by a connecting bond, said bond being under tension in the article when the tufting element is in place with the article compressed between the heads on the ends of the bond, said method comprising automatically attaching an ornamental element such as a button or the like on a head of the tufting element during the placing of said element as follows: placing said button on the shank of a suitable tool, passing said tool through the article until its forward end projects therefrom, attaching one head of the tufting element to said forward end, retracting the tool and drawing the attached head through the article and through the button at the same time compressing the article, and then releasing the pressure on the article and releasing the head from the tool whereby the button is automatically attached to the tufting element during the placing of said element as aforesaid.

3. The method of tufting mattresses, upholstery and the like, which includes the provision of a tufting element comprising an elongated flexible body and a tufting head at each end thereof, positioning one of the tufting heads within a tufting needle and passing the tufting needle with the enclosed tufting head entirely through the body of an article being tufted from one face to the other and at the same time drawing the flexible body after the head, and releasing the held tufting head from the needle when it is beyond the last mentioned face of the article being tufted so that such tufting head engages the last mentioned face of the article being tufted.

4. The method of tufting mattresses, upholstery and the like, using tufting elements severally consisting of two heads permanently connected by a flexible bond or body, the two heads 45 when in normal position being transverse to and impassable through the hole (made by the tool as hereinafter set forth) in the tufted article which receives said flexible bond or body, the method comprising connecting one of said tufting heads to a pointed tool in such a position that it may be passed through the article being tufted, passing said tool with its connected tufting head and bond or body through the article being tufted so as to carry said tufting head completely 55 through the article being tufted and at the same time draw the bond or body through said article being tufted, and releasing said tufting head from the tool so that it may assume its normal position transverse to said hole so that the heads 60 of the tufting element contact the opposite faces of such article.

5. In the method of tufting mattresses, upholstery and the like, the steps of passing one of two heads that are permanently connected by a bonding element to form a complete preformed tufting element completely through the article being tufted while compressing the article, and then releasing the compressed parts of the article so that the heads will be successively and automatically engaged with the opposite faces of the article being tufted in a single movement of the tufting element.

6. The method of tufting mattresses, upholstery and the like, which comprises penetrating 75

- the article being tufted by passing a needle therethrough, attaching one head of a tufting element of suitable length and having a stiffened head connected to each of its ends to the needle and then moving the needle in a reverse direction so that the said one head will be held engaged with the needle by the article during movement of the needle in said reverse direction and continuing movements of the needle until the said one head is moved entirely through the article and then releasing said one head so that both of the heads will engage and contact the respective opposite faces of the article by the single reverse movement of the needle.
15. 7. The method of tufting mattresses, upholstery and the like, which includes employing preformed unitary tufting elements severally consisting of two heads united by a connecting bond, passing a tufting needle through the body of the article being tufted with one of said two heads of the tufting element connected to said needle so as to cause the other of said tufting heads to engage one face of the article being tufted, compressing said article, and releasing the tufting head connected to the needle when it has passed beyond the outer face of the article being tufted so that the two tufting heads will be caused to engage the opposite faces of the article being tufted by the expansion thereof.
30. 8. A method of the character described for connecting the opposite faces of an article by employing preformed elements severally comprising a flexible bond having a head on each end thereof and one of the heads being elongated and having a normal position transverse to the bond, which comprises holding the elongated head in a needle or pointed tool and moving the needle or tool through such article carrying the elongated head endwise along with the needle or tool through the article and at the same time drawing the flexible bond after it, and when the elongated head has been passed completely through such article freeing it from the needle or tool to assume its normal position transverse to the bond so that the heads of the preformed element contact the opposite faces of such article.
50. 9. A process for tufting, consisting of arranging tuftings comprising top and bottom elements joined with a band to the correct size for engaging through a mattress, cushion or the like, releasably engaging one of said elements through the back of a needle, passing said needle through the mattress, cushion or the like so that one of said elements is engaged against one face of the mattress, cushion or the like and the band extends completely through the mattress, cushion and the like, and releasing the element from the needle whereupon it engages against the other face of the mattress, cushion and the like and the tufting is engaged in place.
65. 10. The method of tufting mattresses, upholstery and the like, which includes employing preformed unitary tufting elements severally comprising two heads united by a connecting bond, securing an auxiliary head member such as a button or the like to one of said heads, moving a portion of a tufting needle through the body of the article being tufted with one of said two heads of the tufting element connected to said needle so as to cause said head member to be positioned adjacent the face of the article being tufted, compressing said article, and releasing the tufting head connected to the needle when it has

passed beyond the outer face of the article being tufted and attaching an auxiliary head member to the tufting element adjacent said last named tufting head so that said two auxiliary head members will be caused to engage the opposite faces of the article being tufted by the expansion thereof.

11. A process for tufting, consisting of arranging tuftings comprising top and bottom elements joined with a band to the correct size for engaging through a mattress, cushion or the like, releasably engaging one of said elements with a tufting needle, attaching an auxiliary head member such as a button or the like to one of said tuftings adjacent one of said elements, passing said needle through the mattress, cushion or the like so that said head member is positioned adjacent one face of the mattress, cushion or the like and the band extends completely through the mattress, cushion or the like, and releasing the element from the needle whereupon it engages against the other face of the mattress, cushion and the like and the tufting is engaged in place.

12. A process for tufting, consisting of arranging tuftings comprising top and bottom elements joined with a band to the correct size for engaging through a mattress, cushion or the like, releasably engaging one of said elements with a tufting needle, attaching an auxiliary head member such as a button or the like to one of said tuftings adjacent one of said elements, passing said needle through the mattress, cushion or the like so that said head member is positioned adjacent one face of the mattress, cushion or the like and the band extends completely through the mattress, cushion or the like, releasing the element from the needle, and attaching an auxiliary head member to said tufting adjacent said last named element whereupon it engages against the other face of the mattress, cushion or the like and the tufting is engaged in place.

13. A process for tufting, consisting of arranging tuftings comprising top and bottom elements joined with a band to the correct size for engaging through a mattress, cushion or the like, releasably engaging one of said elements with a tufting needle, passing said needle through the article being tufted so that the other of said elements is engaged against one face of the article being tufted and the band extends completely through the article being tufted, releasing said one element from the needle and attaching an auxiliary head member to said tufting adjacent said one element whereupon it engages against the other face of the article being tufted and the tufting is engaged in place.

14. The method of tufting mattresses, upholstery and the like, which includes passing a preformed tufting element through the article being tufted by means of a tool while the article is under compression, the tufting element comprising a flexible bond having a permanent member at each end, the tufting element having one of its end members engaged in said tool with means on the other free end of the tufting element to engage one face of the article being tufted, releasing the first-mentioned end of the tufting element after it has passed through the article being tufted and attaching a head element to one of the ends of the tufting element.
